James F. Williamson

UNITED STATES PATENT OFFICE.

OLIVE SANDBANK, NOW BY MARRIAGE OLIVE S. CASS, OF NEW YORK MILLS, MINNESOTA, ASSIGNOR OF ONE-FOURTH TO WILLIAM SANDBANK, OF NEW YORK MILLS, MINNESOTA.

BUST-CONFORMING BRASSIÈRE.

Application filed April 17, 1922. Serial No. 553,859.

To all whom it may concern:

Be it known that I, OLIVE SANDBANK, a citizen of the United States, residing at New York Mills, in the county of Otter Tail and State of Minnesota, have invented 5 certain new and useful Improvements in Bust-Conforming Brassières, and I do hereby declare the following to be a full, clear, and exact description of the invention, such 10 as will enable others skilled in the art to which it appertains to make and use the same.

This invention relates to a brassière. Such articles are now commonly worn and 15 especially since the lower neck dresses have become much in vogue. The brassière is used to hold the bust in firm position but no matter how tightly the brassière may be drawn around the body if the body is bent, 20 as in leaning forward, the front portion will loosen and tend to be spaced from the body. With a low neck dress this often results in an undesirable exposure of the bust which is very annoying to the wearer.

25 It is an object of this invention therefore, to construct a brassière which will maintain a comparatively close contact with the form and will prevent an undue opening of the garment at the bust portion or an undue 30 separation of the garment from the body.

It is an object of the invention to construct such a brassière having a stiffened portion at the center thereof, preferably adjacent the top edge, which portion is 35 conformed to the shape of the bust.

These and other objects and advantages of the invention will be fully apparent from the following description made in connection with the accompanying drawings in 40 which like reference characters refer to the same parts throughout the different views and in which—

45 Fig. 1 is a view in front elevation of the extended brassière, a portion thereof being broken out;

Fig. 2 is a top edge view of the central portion of the brassière before the same is formed;

50 Fig. 3 is a similar view showing the formed construction of the brassière and showing a portion of the bust of the wearer in dotted lines;

Fig. 4 is a central vertical section taken

on the line 4—4 of Fig. 1, as indicated by the arrows and shown on an enlarged scale; 55 and

Fig. 5 is a plan view of a stiffening stay which may be used in the brassière.

Referring to the drawings, a brassière of standard design is shown as 1 having the 60 usual hemmed and thickened edge 1^a extended thereabout and being supplied with co-operating fastening members 3 at the sides thereof and with the supporting straps 4 secured to its top edge. The brassière is 65 also provided at its bottom portion with slits or openings 5 disposed at each side of its center adapted to be drawn together and held in desired position by laces.

In accordance with the present invention, 70 the brassière is provided with a stiffened portion shown as 6 which is arranged with its widest portion at the top edge of the brassière and which decreases in width toward the transverse center thereof. In 75

the embodiment of the invention illustrated the stiffened portion is shown as of substantially semi-circular shape and extending to approximately the transverse center portion of the brassière. It will, of course, 80 be understood that the area and extent of the stiffening portion may be considerably varied. The portion 6 is preferably pro-

vided with a plurality of pockets adapted to receive stiffening stays of metal or other 85 material, such as shown at 7 in Fig. 5, the ends thereof being provided with a covering 7^a to obviate any sharp edge. The stiffened

central portion 6 is adapted to be bent inwardly along its center line, as illustrated 90 in Fig. 3. This bend will thus form an inwardly projecting ridge which will have its greatest height at the top edge of the brassière and will gradually taper toward the transverse center thereof. This ridge or 95

bend of the brassière will be formed to fit the bust of the wearer, as indicated in Fig. 3 where the two portions of the bust or breasts are shown as 8. The central bent portion 6^a of the brassière being bent to 100 conform thereto.

When the brassière is worn, the same will be fastened about the form and the inwardly extended portion 6^a will extend into the center of the bust between the side portions 105 thereof and will thus prevent the garments

of the wearer from extending across the two sides of the bust or dropping away from the same unduly. The garments will, on the other hand, be held in close conformity to the bust so that there will be no objectionable opening at the center thereof. The brassière will have great utility with the modern styles of dress and the same can be made at very little extra expense.

10 It should also be stated that the present invention includes such an article of wearing apparel as has been described whether the same is separate or detached. For instance, a certain type of garment is now being worn 15 which is in reality a combination of a corset having few stays and a brassière at the top thereof, which is called a corselette. Applicant's invention could, of course, be applied to the brassière part of such a garment. It is also now common to provide a 20 tight lining for certain dresses, which lining fits tightly about the bust, the dress portion being loosely attached to such lining. Applicant's invention could also equally well be applied to such a dress lining. It is an 25 object of this invention, therefore, to embrace any article of wearing apparel adapted to be tightly drawn about the bust which has a stiffened portion adapted to conform 30 to and fit between the bust portions.

It will, of course, be understood that various changes may be made in the form, details and proportions of the device without departing from the scope of applicant's invention, which, generally stated, consists in 35

the matter shown and described and set forth in the appended claims.

What is claimed is:

1. A brassière comprising a strip of flexible material adapted to embrace the body 40 across the busts, and including a continuous stiffened member which extends inwardly toward the body between the busts, said member being provided, on each side, with a curved portion adapted to conform to the 45 inner sides of the busts.

2. A brassière comprising a strip of flexible fabric material adapted to extend around the body of the wearer substantially 50 in line with the busts, said strip having a centrally located stiffened portion at its front, said portion being bent inwardly to fit between the busts, and provided with spaced, longitudinally-positioned stiffening members extending across said stiffened portion, said members decreasing in length 55 towards the bottom of said stiffened portion.

3. A brassière comprising a strip of flexible material adapted to embrace the body of the wearer substantially at the bust line, 60 said strip having an area at its front central portion formed by stiffened members extending longitudinally of said strip across said area, said members being bent inwardly to form a trough adapted to extend transversely between the busts of the wearer, the portion of said strip in front of and at the outer side of said busts being flexible.

In testimony whereof I affix my signature.

OLIVE SANDBANK.
